WINDOW

Peter J. Flammang, Beech Grove, Ind.

Application April 17, 1933, Serial No. 666,460

3 Claims. (Cl. 296—44)

The object of my invention is to produce a vertically slidable window sash comprising one section which may be swung about an axis which is parallel with the plane of the movement of the sash, together with mechanism by which, through the medium of a single operating shaft, the sash may be vertically adjusted when and only when the swinging element is in the sash plane, and the swinging element may be angularly adjusted when and only when the sash is at one extreme of its vertical movement.

The mechanism is primarily designed for automobile doors where the sash comprises a glass fixed relative to the sash plane and a coordinated glass angularly adjustable relative to the sash plane and wherein angular adjustability of the last-mentioned glass is desired when the sash is at its upper, compartment-closing, extreme.

The accompanying drawing illustrates my invention:

Fig. 1 is a side elevation of my mechanism together with fragmentary portions of cooperating door jams and window sash;

Fig. 2 is a fragmentary horizontal section, on a larger scale, of parts shown in Fig. 1;

Fig. 3 is a section on line 3—3 of Fig. 1; and

Fig. 4 is an elevation, in fragmentary vertical section, of the parts shown in Fig. 2.

In the drawing 10, 10 indicate two door jams between which is secured, to the inside of the plane of the vertically sliding sash S, a base bar 11 which may be conveniently formed of angle or channel iron.

Mounted upon the top of bar 11 is a bracket 12 in which is journalled a horizontal operating shaft 13, the inner end of which is provided with a suitable crank (not shown) by means of which it may be rotated.

Within the thickness of the door, shaft 13 is provided with a quick pitch screw 14 upon which is threaded a sleeve 15 the outer end of which carries a gear 16. Shaft 13, at its outer end, carries a flange 17 which limits axial movement of the sleeve 15 in that direction and carries a collar 18 which limits axial movement of sleeve 15 in the opposite direction. Shaft 13 also carries a collar 19 adjacent collar 18 and between these two collars lies the inside finish plate 20 of the door.

Journalled in bracket 12 parallel with shaft 13 is a shaft 25 provided with a worm 26 and a pinion 27 capable of meshing with gear 16.

Mesning with worm 26 is a worm wheel 28 carried by a shaft 29 which lies at a right angle to

shafts 13 and 25 and is journalled in brackets 30, 30 secured to the top side of bar 11.

Shaft 29 near each end carries a sprocket wheel 31 over each of which is an endless belt comprising a section of links 32, adapted to mesh with the sprocket wheel, and a section 33 of steel tape which is passed under and around an idler 34 carried by a vertically movable yoke 35 mounted in a bracket 36 secured to the adjacent jam 10 and normally urged downwardly, so as to maintain proper tension in the endless belt 32—33, by a spring 37. Each of the endless belts 32—33 carries a fork 39 provided with a slot 40. One of these forks 39 receives the lower wall 41 of a box-like metal hanger 42 attached to the under edge of the lower rail of the sash S, as shown in Fig. 3.

Also secured to the lower edge of the lower rail of sash S is a box-like hanger 45 the lower wall 44 of which is received in the other fork 39.

Journalled in suitable bearings 46 in hanger 45 is a shaft 47 parallel with shafts 13 and 25 and this shaft carries the worm 48 and the pinion 49 which may mesh with gear 16. Also journalled in bearings in hanger 45 and in the lower rail of sash S is a vertical shaft 50 provided with a worm wheel 51 which meshes with worm 48. The lower end of shaft 50 carries an eccentric pin 52 which is projected into a slot 53 formed in a slide 54 which is slidably mounted in hanger 45 and provided with an upright post 55 having a horizontal upper end 56 which is projected into one end of a safety latch 57 slidably mounted in the hanger and lying alongside of pinion 49.

Secured to hanger 45 is a bracket 60 provided with an inwardly extending horizontal pin 61 which may traverse an inclined cam slot 62 carried by a laterally slideable safety latch 63 which is arranged alongside the outer face of pinion 27, said latch being slotted at 64 to straddle shaft 25 and slotted at 65 to straddle a pin 66 carried by bracket 67 secured to the top of bar 11.

Near its inner end sleeve 15 is radially bored to form a pocket for a latch ball 70 yieldingly urged inwardly by spring 71 attached to sleeve 45 and adapted to lie in either one of two circumferential grooves 72 and 72' formed in shaft 13 at the inner end of threads 14.

The sash S is provided with a fixed glass section G and a complementing swinging glass section G' which section at its lower edge is mounted in holder 50' attached to the upper end of shaft 50.

The upper edge of this swinging glass section will be provided with a fulcrum pin bracket of 55

well known form (not shown) in alignment with shaft 50 and journalled in the upper rail of the sash S.

The parts are shown in the positions which they occupy when the sash S is in its upper extreme and glass G' lies in the plane of glass G and sleeve 15 is at an intermediate transit position between the two pinions 27 and 49 and by turning shaft 13 counter-clockwise gear 16 will be shifted axially into full mesh with pinion 49 and out of mesh with gear 27 and ball 70 will drop into groove 72'. Thereupon the shaft 13 may be rotated in a counter-clockwise direction thus rotating pinion 49 and worm 48 in a clockwise direction so as to rotate shaft 50 in a clockwise direction (Fig. 2) thereby swinging one edge of glass G' outwardly and setting the glass G' at an angle to the plane of glass G. Counterclockwise movement of shaft 13, by reason of screw 14, tends to hold gear 16 in its outermost position on shaft 13. As the shaft 50 is rotated in a clockwise direction its pin 52, through the medium of slide 54, post 55, and finger 56 shifts the safety latch 57 to the left (Fig. 2) so as to overlie gear 16. Within the limits of the oscillatory movement of shaft 50 shaft 13 may be moved in either direction to swing glass G' from or to closed position, i. e., into parallelism with glass G, ball 70, as well as latch 57 preventing axial movement of gear 16, with its sleeve 15, on shaft 13 during clockwise movements of said shaft. As glass G' approaches parallelism with glass G latch 57 is fully retracted from gear 16 and when the glass G' is brought to its seat furnishes sufficient resistance to permit screw 14 to cause gear 16 to be retracted toward and into mesh with pinion 27 and out of mesh with pinion 49.

When gear 16 first meshes with pinion 27 glass 40 G' will be in parallelism with glass G, and the axial shifting of gear 16 takes place without rotation and ball 70 is shifted from groove 72' into groove 72. When sleeve 15 abuts collar 18 and gear 16 fully meshes with pinion 27, clockwise 45 movement of shaft 13 rotates shaft 25 counter-clockwise.

Continued counter-clockwise movement of pinion 27 operates through worm 26, worm wheel 28, shaft 29, sprockets 31 and the endless belts 50 32-33 to draw the sash S downwardly, pinion 49 moving downwardly with the sash. The initially downward movement of the sash drives pin 60 downwardly through the cam slot 62 and shifts the safety latch 63 to a position to overlap the 55 outer face of gear 16, said latch being yieldingly held at either extreme of its position by a spring latch ball 79 of well known construction mounted in bracket 67.

In this position of the parts the shaft 13 may 60 be rotated either clockwise or counter-clockwise to lower or raise the sash S. As sash S approaches its upper limits, due to counter-clockwise movement of shaft 13, pin 61 will again traverse cam slot 62 in the opposite direction so as to retract latch 63 from its overlap on gear 16 and, as the sash reaches its upper limit it offers sufficient resistance to permit screw 14 to shift gear 16 from its mesh with pinion 27 and into mesh with pinion 49 whereupon the operation may be 65 repeated.

It will be noted that, while manipulation of shaft 13 may produce either vertical adjustment of the sash as a whole or angular adjustment of the swinging glass G', there can be no vertical 70 adjustment of the sash until the glass G' is in

parallelism with glass G, and there can be no angular movement of glass G' except when the sash S is in its upper limit.

As a precaution against displacement of pinion 49, due to rattling or otherwise, during those periods when the sash S is in a lowered position I provide an automatic friction brake comprising a friction shoe 80 carried by a stem 81 vertically slideable in a bracket 82 secured to the underside of hanger 45. The shoe 80 is yieldingly urged upwardly by a spring 83 which is held against angular displacement by a pin 84 sliding in a slot 85 in bracket 82. The stem 81 is provided at its lower end with a laterally projecting finger 86 which may be brought into contact with a finger 87 attached to bar 11.

When the sash S nears the limit of its upward movement finger 86 is brought up under finger 87 and stem 81 is held against further upward movement so that the final upward movement of the sash retracts shoe 80 from frictional contact with pinion 49. Upon initial downward movement of sash S from its upper limit bracket 82 moves downwardly and spring 83 moves shoe 80 upwardly into contact with pinion 49 and remains in that frictional contact while the sash S is in all of its lower positions.

I claim as my invention:

1. The combination with a sash carrier and a slideable sash mounted therein and comprising a swinging section, of an operating shaft journalled on the carrier, a shaft journalled on the sash and engaging the swinging section, a driving train for said last-mentioned shaft mounted on the sash and comprising a pinion, a driving train 30 mounted on the sash carrier and comprising a pinion and means for engaging the sash to shift the same in the sash carrier, an operating gear mounted on the operating shaft, means by which said gear may be shifted into mesh with either of said pinions, a safety latch movable into and out of position to restrain separation of the operating gear from the pinion of the driving train of the swinging sash section, means operated by said last-mentioned train for moving said safety latch, a second safety latch movable into and out of position to restrain separation of the operating gear from the pinion of the sash shifting train, and means dependent upon sliding movement of the sash for shifting said second safety latch into and out of position restraining separation of the operating gear from the pinion of the sash shifting train.

2. The combination with a sash carrier and a slideable sash mounted therein and comprising a swinging section, of an operating shaft journalled on the carrier, a shaft journalled on the sash and engaging the swinging section, a driving train for said last-mentioned shaft mounted on the sash and comprising a pinion, a driving train 40 mounted on the sash carrier and comprising a pinion and means for engaging the sash to shift the same in the sash carrier, an operating gear mounted on the operating shaft and axially shiftable thereon into and out of mesh respectively with said two pinions, a threaded connection between the operating shaft and operating gear, means to limit axial movement of the operating gear on the operating shaft due to rotation of the operating shaft relative to the 45 operating gear, and yielding means to restrain axial movement of the operating gear on the operating shaft.

3. Apparatus of the character specified in claim 2 comprising a safety latch movable into and out 50

of position to restrain separation of the operating gear from mesh with the pinion of the driving train of the swinging sash section, means operated by said last-mentioned train for moving said safety latch, a second safety latch movable into and out of position to restrain separation of the operation gear from the pinion of the sash

shifting train, and means dependent upon sliding movement of the sash for shifting said second safety latch into and out of position restraining separation of the operating gear from the pinion of the sash shifting train.

5
